Inventor:

William Stelzer

UNITED STATES PATENT OFFICE.

WILLIAM STELZER, OF CHICAGO, ILLINOIS.

SANITARY TOILET COVER.

Application filed November 24, 1926. Serial No. 150,511.

My invention relates to a mechanism holding a standard toilet paper roll and fastened on the toilet seat; and the objects of the improvement are, first to provide a fresh supply of sanitary cover for every occupant of the seat, second to facilitate the placing of the fresh one on, and third to prevent the wasting of the regular toilet paper in using it as seat-cover.

10 I attain these objects by the mechanism illustrated in the accompanying drawing in which:

Figure 1 shows the entire mechanism mounted on the lower part of the toilet seat.

15 Figure 2 shows the end of the sanitary cover roll placed on the seat.

In Figure 3 two mechanisms are seen mounted sideways on the seat with two sanitary covers in use.

20 Figure 4 shows another application of the mechanism as it can be mounted on the seat.

Figure 5 refers to the holding mechanism for the toilet paper roll.

25 Similar numerals refer to similar parts throughout the several views.

The standard toilet paper roll 1, placed around the wooden rod 2, will be held in position by a metal rod or wire 3, with the bent ends protruding into the wooden rod 2, the reinforcing wire 10 presses the holding wire 3 against the rod 2, and prevents a slipping off the paper rolls, at the same time allows its easy turning.

30 The ends 6, of the sanitary roll pulled in the direction of the arrows 4 and 5, can be placed easily on the seat, furnishing the user with a fresh layer of sanitary cover on such parts of the seat, which are mostly exposed,

to be soiled by previous users of the toilet seats.

35 The used end 6, of the sanitary cover can be removed from the roll by taking said end, and pulling the paper in the direction of arrow 5, thereby pressing it against the cutting edge 7, which is rigidly mounted on the 40 helical formed metal casing 8 of the sanitary roll, by means of a bent strip 9, which latter serves also as a mounting for the entire mechanism.

45 Pressing the ends 15 and 16, of the holding wire 3, in the directions indicated by the arrows 17 and 18 respectively, the wooden rod 2, can be removed from the protruding edges 11 and 12 of the holding wire 3, and the new sanitary roll can be put in service.

50 The end 13 of the metal casing 8 forms an almost closed cylinder around the middle part 14 of the wire 3 and around the helical part of the reinforcing wire 10, and so protecting them.

55 I am aware that prior to my invention sanitary toilet-seat covers have been made, I therefore do not claim such a combination broadly; but

60 I claim:

65 In a device of the class described a sheet metal helical casing formed of one piece and open at the sides, a paper roll incased in said casing provided with resilient arms attached to the casing to permit the roll to be removed from the casing, a bracket secured to the under side of the toilet seat, said bracket having a cutting bar attached to the forward edge, and means for attaching the helical casing to the bracket.

WILLIAM STELZER.
